ABSTRACT: The contact tips of the reeds in a reed switch are rounded and all sharp corners removed. The result is a significant improvement in contact isolation characteristics at high frequencies when the switch is open.

REED SWITCH WITH IMPROVED CONTACT ISOLATION

This invention relates to reed switches and, more particularly to the switch contact portion of reeds used therein.

Reed switches are well known and in widespread use. They generally include a pair of thin reedlike contacts cantilever supported and hermetically sealed through opposite respective ends of an elongated glass envelope with their tips in fairly close spaced opposition. The reeds are of a magnetically permeable material, and their tips are brought together to close the switch by the application of a magnetic field. When the field is removed, the switch opens.

Such switches have found great utility in a wide number of applications because they are compact, dependable in any atmosphere, very sensitive, fast acting, and have a relatively rapid cycling rate. However, concomitant with these advantages, the physical closeness and configuration of the reeds is such that they appear to have an interelement capacitance which must be considered when they are being used in switch matrices to isolate circuits carrying alternating current signals, the degree of isolation provided by such reed switches becoming less effective at a logarithmic rate as signal frequency increases.

In prior art reed relays, the tips of the switch contact ends of the reeds either have sheared, sharply edged contours, or else have such sheared edges broken by a slight chamfer, and heretofore the best contact isolation levels that could be achieved in reed switch matrices handling signals of about 50 to 60 MegaHertz have been approximately 55 to 60 db. below the level of the signal. For high quality systems, further reduction is highly desirable.

The invention herein is based upon the discovery that circuit isolation provided by reed switches can be improved if the end contours of the switch contact portions of individual reeds are given a full radius. Briefly, in accordance with the present invention, it has now been found that simply rounding off the tips of the reeds in reed switches, to avoid sharp corners in their overlapping portions enables the achievement of contact isolation levels approximately 65 to 75 db. down when dealing with signals in the range of about 50 to 60 MegaHertz. The reason for the improved results is not understood, although it is thought that they may be related to the well-known edge effect in electrostatics.

According to the subject invention, a reed for use in a reed switch capsule comprises a terminal portion adapted for attachment to a support by said capsule and a switch portion with a tip having full radius curvatures for height and width end contours.

The invention will now be described with greater particularity, reference being made to the accompanying drawings in which:

FIG. 1 is a side elevational view of a reed switch according to the invention herein:

FIGS. 2A and 2B are side and plan views, respectively, of the switch contact portions, greatly enlarged, of a pair of the most common type of prior art reed:

FIGS. 3A and 3B are views similar to FIGS. 2A and 2B of a pair of another type of prior art reed; and

FIGS. 4A and 4B are greatly enlarged views of the switch contact portions of a pair of reeds according to the invention herein.

In FIG. 1, a pair of reeds 10 have cantilevered switch contact portions 13 adjoining and extending from terminal portions 12. The cantilevered portions 13 have rounded tips 14, and the reeds 10 are hermetically sealed within elongated

glass capsule 16. Respective terminal portions 12 are attached to the ends of capsule 16 so that switch contact portions 13 are cantilever supported in overlapping relation near the center of the capsule.
